KNIT FABRIC

Joseph Rab, Los Angeles, Calif., assignor to Kayser-Roth Corporation, New York, N.Y., a corporation of New York

Filed Mar. 7, 1961, Ser. No. 94,018
10 Claims. (Cl. 66—202)

This invention relates generally to a jersey knit fabric which is provided with a plurality of spaced apart ribs extending outwardly from and walewise on one face of the fabric and more particularly to a fabric in which the body fabric between the walewise ribs is formed of a textured synthetic stretchable yarn.

It is generally well known to produce various types of knit fabric by combining plain, tuck and/or welt or float stitches. However, a jersey knit fabric has not heretofore been produced by combining these stitches to form a fabric which has a plurality of spaced apart walewise ribs which are knit of a relatively heavyweight yarn and a stretchable body fabric which is knit of a relatively lightweight stretchable yarn in the wales between the walewise ribs and form tucks extending across the wales in which the walewise ribs are knit.

It is a primary object of the present invention to provide a jersey knit fabric which resembles a true rib fabric and which may be economically knit in quantity on existing knitting machinery.

It is another object of the present invention to provide a knit fabric of the type described above in which the body fabric is knit of relatively lightweight textured synthetic stretchable yarns and the walewise ribs on one face are knit of a relatively heavyweight yarn and which knit fabric is stretchable whereby the knit fabric may be used in the manufacture of many types of wearing apparel, such as bathing suits, shirts, dresses or in the forming of the cuff and waist bands of knit sweaters and the like.

It is a further object of the present invention to provide a jersey knit fabric of the type described above in which the body fabric yarns and the yarns producing the walewise ribs may be different colors or the yarns may be formed of different types of material so that their dye receiving capabilities may be different so that the walewise ribs may be a different color than the color of the body fabric.

It is a more specific object of the present invention to provide a jersey knit fabric of the type described above in which the stretchable yarns are knit in groups of wales between the walewise ribs and form tucks extending across the wales in which the ribs are formed while the ribs are formed by stitch loops of the heavier yarn which are knit in spaced apart courses only and the stitch loops of the heavier yarn in each rib wale are connected to the stitch loops of the heavier yarn in adjacent rib wales by floats extending across the inner face of the fabric and the medial portions of these floats are knit in a central wale of the groups of wales in which the stretchable yarns are knit to provide a relatively smooth inner face on the fabric, as compared to the ribbed outer face thereof.

Some of the objects of the invention having been stated, other objects will appear as the description proceeds, when taken in connection with the accompanying drawings, in which—

FIGURE 1 is a fragmentary elevational view of the ribbed or outer face of the jersey knit fabric of the present invention and showing the same in relaxed or un-stretched condition;

FIGURE 2 is an enlarged horizontal sectional view through a portion of the knit fabric shown in FIGURE 1, somewhat schematically illustrating the stretchable base fabric with the outstanding walewise ribs on the outer

2

face and the floats extending along the inner face of the fabric;

FIGURE 3 is a greatly enlarged elevation of a small area of the jersey knit fabric shown in FIGURE 1 with the fabric being stretched in a coursewise direction;

FIGURE 4 is a view similar to FIGURE 3, however, in this view, the fabric is illustrated somewhat schematically in that the stitch loops have been substantially aligned coursewise and walewise to more clearly illustrate the manner in which the fabric is formed.

Referring to FIGURE 1, it will be noted that the jersey knit fabric of the present invention includes a stretchable base or body fabric, broadly indicated at 10, having a plurality of spaced apart walewise extending ribs, broadly indicated at 11. As shown in FIGURE 2, the ribs 11 stand out from the outer face of the base fabric 10 and when the fabric is in relaxed or unstretched condition, the ribs 11 are drawn close together.

As shown in FIGURES 3 and 4, the stretchable base fabric 10 is formed of knit stitch loops of relatively lightweight stretchable yarns, indicated at S-1, S-2 and S-3, which form plain stitches in the wales between the wales in which the ribs 11 are knit. The lightweight stretchable yarns extend across the wales in which the ribs 11 are knit and form tucks, indicated at T, in these wales. The lightweight stretchable yarns are preferably formed of multifilament thermoplastic synthetic yarns which have been texturized by any one of many well known processes to impart a permanent crimp or curl to the individual filaments.

The walewise extending ribs 11 are formed of knit stitch loops of relatively heavyweight yarns Y which are knit in spaced apart needle wales and floated across and behind intervening needle wales. The heavyweight yarns Y are preferably non-stretchable and formed of natural fibers, such as spun cotton. However, it is to be understood that the yarns Y may be formed of other types of natural or synthetic fibers and they may be stretchable or non-stretchable as long as they are of a heavier weight or denier than the yarns which form the base fabric 10. One repeat of the fabric is shown in courses C-11 through C-14 and wales W-11 through W-14 of FIGURE 4 and any desired length and width of fabric may be formed by repeating the coursewise and walewise repeat the desired number of times.

As shown in the schematic illustration of the fabric in FIGURE 4, the lightweight stretchable yarns S-1, S-2 and S-3 form stitch loops in groups of successive courses C-11, C-12, C-13 and C-15, C-16, C-17 and in groups of adjacent wales W-8, W-9 and W-11, W-12, W-13 and W-15, W-16 and extend across and form tucks T in the single wales W-10 and W-14 positioned between the groups of adjacent wales. The heavyweight yarns Y form stitch loops in spaced apart single courses C-10, C-14, C-18 and in alternate wales W-8, W-10, W-12, W-14, W-16 of these courses. In these spaced apart single courses the yarns Y are floated across and behind intervening wales W-9, W-11, W-13, W-15 to form floats F which extend along the inner face of the base fabric 10 (FIGURE 2).

After the fabric has been finished, the stretchable yarns act to draw the rib 11 together and the knit stitches of the yarn Y in wales W-8, W-12, W-16 and in courses C-10, C-14, C-16 do not appear on the outer face of the fabric. As shown in the stretched fabric of FIGURE 3, the stitch loops of heavyweight yarn Y (shown in wales W-8, W-12, W-16 of FIGURE 4) straighten out, thereby pulling the knit stitch loops of lightweight stretchable yarn, which are connected thereto, through the previously formed stitch loops of lightweight stretchable yarn. Thus, as shown in FIGURE 3, the floats F of the heavy yarn Y are tied to the base fabric 10 in

wales W-8, W-12, W-16, however, the yarn Y is not visible on the front face of the fabric in these wales. When the fabric is relaxed, the stitch loops of the stretchable yarns contract to draw the walewise extending ribs 11 together and contract the fabric in both coursewise and walewise directions. Also, since the stretchable yarn contracts when relaxed, the tucks T of the lightweight stretchable yarns try to straighten out, causing the stitch loops of the non-stretchable heavyweight yarn Y in wales W-10, W-14 to protrude outwardly on the outer face of the fabric and appear large and loose, as compared to the stretchable yarn stitch loops of the body fabric 10.

The simulated rib fabric of the present invention may be economically produced on a conventional circular jersey knitting machine which is provided with a plurality of feeding and knitting stations in multiples of four. In knitting the fabric on this type of circular knitting machine, the stretchable yarns S-1, S-2 and S-3 are fed to all of the needles at three consecutive respective knitting stations and plain jersey stitch loops are formed on groups of three successive needles while the stretchable yarns are tucked on every fourth needle. Thus, course C-11 is formed by feeding the yarn S-1 to all of the needles at a first feeding station. At this first feeding station, the needles in wales W-8, W-9, W-11, W-12, W-13, W-15, W-16 are lowered to form stitch loops while the needles in wales W-10 and W-14 pass this station at tuck level and take the yarn S-1 in their hooks but do not form stitch loops therewith. At the second knitting station, the yarn S-2 is fed to the needles in the same manner as the yarn S-1 to form course C-12 and the yarn S-3 is fed to the needles at the third knitting station in the same manner as the yarns S-1 and S-2 to form course C-13.

At the fourth knitting station, the relatively heavyweight non-stretchable yarn Y is fed to and forms stitch loops in wales W-8, W-10, W-12, W-14, W-16 of course C-14. Thus, stitch loops are formed on alternate needles at this fourth knitting station and the intervening needles are not raised high enough to receive the yarn Y in their hooks. As the needles in wales W-10 and W-14 are raised to shed level and then lowered to stitch drawing level, the tucks of yarns S-1, S-2, S-3 are shed as a stitch loop is formed in these wales of course C-14. During the formation of course C-14, the needles in wales W-9, W-11, W-13, W-15 are raised to welt level and do not take the non-stretchable yarn Y in their hooks at this fourth knitting station so that the yarn Y is merely floated inside of the fabric and behind the stitch loops in these wales. The courses C-15 through C-18 are identical to the courses C-11 through C-14 described above and are formed at the next four successive knitting stations on the machine.

It has been found that a very satisfactory fabric is produced by feeding multifilament nylon 40/2 denier nylon stretch yarn, of the type known as Helanca, at groups of three consecutive feeding stations of an 18-cut Supreme sinker top circular knitting machine while feeding two ends of 16/1 combed cotton yarn at single feeding stations located between the groups of consecutive feeding stations at which the stretchable yarn is fed. By using lightweight stretchable synthetic yarns to knit the body or base fabric 10 and a heavyweight cotton yarn to knit the walewise ribs 11, unusual coloring effects may be achieved by cross-dyeing or by using pre-dyed yarns of different colors. If desired, the fabric of the present invention may be produced in only portions of a jersey knit plain fabric.

Although a specific construction of knit fabric is disclosed as being knit on a specific type of knitting machine, it is to be understood that other constructions and other types of yarn may be utilized if desired and the fabric may be knit on other types of knitting machines than the circular machine described. For example, a greater number of wales knit of the stretchable

yarns could be formed between the outwardly extending ribs 11 formed of the heavyweight yarn. Also, although it is desirable to tie the floats of the heavyweight yarn Y into the base fabric between the ribs 11, the floats F of the yarn Y may extend from one rib 11 to the next rib 11 without being interknit with the wales therebetween. Also, the number of courses knit of lightweight stretchable yarn before knitting a course of heavyweight yarn may be varied, as desired.

The simulated rib jersey knit fabric of the present invention is useful in forming many types of garments and may be knit tubular or flat. The fabric is stretchable in both coursewise and walewise directions and the walewise extending ribs impart a distinctive and bulky appearance thereto.

In the drawings and specification there has been set forth a preferred embodiment of the invention, and although specific terms are employed, they are used in a generic and descriptive sense only and not for purposes of limitation, the scope of the invention being defined in the claims.

I claim:

1. A jersey knit fabric comprising a stretchable body fabric and a plurality of spaced apart walewise ribs extending outwardly from one face of said body fabric, said body fabric being knit of relatively lightweight stretchable yarns knit in groups of successive courses and wales, said stretchable yarns being tucked in single wales positioned between said groups of successive wales, and said walewise ribs being knit of relatively heavyweight yarns knit in said single wales between said groups of successive wales and in a single course positioned between each of said groups of successive courses.

2. A jersey knit fabric comprising a stretchable body fabric and a plurality of spaced apart walewise ribs extending outwardly from one face of said body fabric, said body fabric being knit of crimped multifilament thermoplastic stretch yarns knit in groups of successive courses and wales, said stretch yarns being tucked in single wales positioned between said groups of successive wales, and said walewise ribs being knit of cotton yarns knit in said single wales between said groups of successive wales and in a single course positioned between each of said groups of successive courses, said cotton yarns being of a heavier weight than said stretch yarns.

3. A jersey knit fabric comprising a stretchable body fabric and spaced apart ribs extending walewise on the outer face of said body fabric, said body fabric being knit of stretch yarns knit in spaced apart groups of a predetermined number of successive courses and wales, said stretch yarns forming tucks extending across single wales positioned between said spaced apart groups of successive wales and in each course of said groups of successive courses, said walewise ribs being knit of a heavier yarn than said stretch yarns, said heavier yarn being knit in the single wales containing said stretch yarn tucks and in a single course positioned between each of said groups of successive courses, and said heavier yarn having floats extending along the inner face of said body fabric and between the single wales containing said stretch yarn tucks.

4. A jersey knit fabric comprising a stretchable body fabric and spaced apart ribs extending walewise on the outer face of said body fabric, said body fabric being knit of stretch yarns knit in spaced apart groups of a predetermined number of successive courses and wales, said stretch yarns forming tucks extending across single wales positioned between said groups of successive wales and in each course of said groups of successive courses, said walewise ribs being knit of a heavier yarn than said stretch yarns, said heavier yarn being knit in the single wales containing said stretch yarn tucks as well as in medial wales of said groups of successive wales and in a single course positioned between each of said groups of successive courses, and said heavier yarn having floats extending along the inner face of said body fabric and between the

single wales containing said stretch yarn tucks and the medial wales of said groups of successive wales.

5. A jersey knit fabric comprising a stretchable body fabric and spaced apart ribs extending walewise on the outer face of said body fabric, said body fabric being knit of stretch yarns knit in spaced apart groups of three successive courses and wales, said stretch yarns forming tucks extending across single wales positioned between said three successive wales and in each of said three successive courses of said groups, said walewise ribs being knit of a heavier yarn than said stretch yarns, said heavier yarn being knit in the single wales containing said stretch yarn tucks as well as in the center wale of said groups of three successive wales and in a single course positioned between each of said groups of three successive courses, and said heavier yarn having floats extending along the inner face of said body fabric and between the single wales containing said stretch yarn tucks and the center wale of said groups of successive wales.

6. A jersey knit fabric comprising a stretchable body fabric and spaced apart ribs extending walewise on the outer face of said body fabric, said body fabric being knit of crimped multifilament thermoplastic stretch yarns knit in spaced apart groups of a predetermined number of successive courses and wales, said stretch yarns forming tucks extending across single wales positioned between said groups of successive wales and in each course of said groups of successive courses, said walewise ribs being knit of a cotton yarn that is heavier than said stretch yarns, said cotton yarn being knit in the single wales containing said stretch yarn tucks and in a single course positioned between each of said groups of successive courses, and said cotton yarn having floats extending along the inner face of said body fabric and between the single wales containing said stretch yarn tucks.

7. A jersey knit fabric comprising a stretchable body fabric and spaced apart ribs extending walewise on the outer face of said body fabric, said body fabric being knit of crimped multifilament thermoplastic stretch yarns knit in spaced apart groups of a predetermined number of successive courses and wales, said stretch yarns forming tucks extending across single wales positioned between said groups of successive wales and in each course of said groups of successive courses, said walewise ribs being knit of a cotton yarn that is heavier than said stretch yarns, said cotton yarn being knit in the single wales containing said stretch yarn tucks as well as in a medial wale of said groups of successive wales and in a single course positioned between each of said groups of successive courses, and said cotton yarn having floats extending along the inner face of said body fabric and between the single wales containing said stretch yarn tucks

and said medial wale of said groups of successive wales.

8. A jersey knit fabric comprising a stretchable body fabric and spaced apart ribs extending walewise on the outer face of said body fabric, said body fabric being knit of crimped multifilament thermoplastic stretch yarns knit in spaced apart groups of three successive courses and wales, said stretch yarns forming tucks extending across single wales positioned between said three successive wales and in each of said three successive courses of said groups, said walewise ribs being knit of a cotton yarn that is heavier than said stretch yarns, said cotton yarn being knit in the single wales containing said stretch yarn tucks as well as in the center wale of said groups of three successive wales and in a single course positioned between each of said groups of three successive courses, and said cotton yarn having floats extending along the inner face of said body fabric and between the single wales containing said stretch yarn tucks and the center wale of said groups of successive wales.

9. A jersey knit fabric having a plurality of spaced apart walewise ribs on one face thereof, the stitch construction forming said walewise ribs repeating every four wales and every four courses, each repeat including a relatively lightweight crimped multifilament thermoplastic stretch yarn knit in the first three wales and tucked in the fourth wale of each of the first three courses, and a relatively heavyweight cotton yarn knit in the second and fourth wales of only the fourth course and floated across the first and third wales thereof.

10. A jersey knit fabric having a plurality of spaced apart walewise ribs on one face thereof, the stitch construction forming said walewise ribs repeating every four wales and every four courses, each repeat including a relatively lightweight stretch yarn knit in the first three wales and tucked in the fourth wale of each of the first three courses, and a relatively heavyweight cotton yarn knit in at least the fourth wale of only the fourth course and floated across at least the first and third wales thereof.
